UNITED STATES PATENT OFFICE.

FRIEND W. SMITH, OF BRIDGEPORT, CONNECTICUT, ASSIGNOR TO THE SMITH & EGGE MANUFACTURING COMPANY, OF SAME PLACE.

DRAWER-PULL.

*SPECIFICATION forming part of Letters Patent No. 253,437, dated February 7, 1882.

Application filed December 29, 1881. (Model.)

To all whom it may concern:

Be it known that I, FRIEND W. SMITH, a citizen of the United States, residing at Bridgeport, in the county of Fairfield and State of Connecticut, have invented certain new and useful Improvements in Drawer-Pulls, of which the following is a specification, reference being had therein to the accompanying drawings.

My invention relates to drawer-pulls, and 10 more especially to that class provided with drop or pivoted handles. It has for its object facility in use, simplicity of construction, and economy in price; and with these ends in view my invention consists in the details of construction and combination of elements, as will be hereinafter fully and specifically set forth.

In order that those skilled may understand the construction and operation of my improved drawer-pull, I will proceed to describe the same 20 in detail, referring by letter to the accompanying drawings, in which—

Figure 1 is a perspective view of a drawer with my improved drop-handle attached; Fig. 2, a vertical longitudinal section at right angles 25 to the plane of movement of the drop-handle; and Figs. 3, 4, 5, 6, 7, and 8, detail views of several modifications of flat shank, tubular shank, and ornamental plug, and side elevation of drawer-pull secured to drawer by means of 30 wedge-shaped key.

A is any ordinary wooden knob or handle, having a central longitudinal opening or channel, *a*, into which a tube, B, is driven, as shown at Fig. 2.

C is the shank, and consists of a flat piece of sheet metal punched out into the necessary shape. Near the extreme end of said shank is a slot for the reception of a wedge-shaped key. This shank I preferably make of a tapering 35 shape, in order that the shank may be adapted to enter or be forced into a smaller slot or hole in the drawer, the result being that the shank forms its own bearings, and is thereby held rigidly in position. As seen at Fig. 4, the 40 shank may be notched on its edges for the purpose of tearing away the sides of a smaller slot or hole in the drawer. It is obvious that in this latter case the shank may or may not be tapered, as the notches act as saw-teeth in 45 either case.

When desirable, instead of a key and slot, as above mentioned, I form a thread on the edges of the shank and fasten the drawer-pull by a nut. This shank C, I form with a shoulder, and rivet it or otherwise rigidly secure it 55 to the yoke D.

E is a cap or ferrule, which is placed over the tube B in such manner that the holes *b* in the former come into alignment with the holes *c* in the latter. The yoke D is pivotally attached 60 to the cap and tube by a pin headed at both ends.

F is an ordinary plug, which is driven into the tube B at the knob end for the double purpose of spreading or beading the tube at 65 that point, so that the same cannot be withdrawn from position, and of affording an ornamental center to the knob A at its lower or drop end. It is obvious that this plug may be made of wood or metal. If the former, then 70 the center-piece is provided by driving into the wood any ornamental tack, screw, button, &c., and if the latter the plug can be solid or hollow, and is made so as to project above the surface of the handle, and is itself ornamental. 75 It is not necessary to unite the edges of the tube B; but I prefer to leave them slightly apart, as shown at Fig. 6, so that they may be contracted or expanded to adapt said tube to any slight variation in the size of the channel 80 *a*. The tube is made of such length as to project beyond the inner end of the handle a suitable distance for the purpose of the reception of a ferrule, as hereinbefore explained.

The channel *a* may be countersunk or enlarged at the outer end of the handle, so that the plug, when forced into the tube B, as described, will not be liable to split the said handle.

In assembling the parts I usually force the 90 tube into the channel *a* of the handle, put on the ferrule, and attach the yoke thereto, as described. I then with a proper tool flange the tube at its plug end, which shortens it and draws it up tight. I then drive in the plug, 95 which binds said tube against the walls of the channel *a*, thereby preventing it from turning in said channel, and then affix the ornamental center. I preferably bore a small round hole in the drawer, since it is more convenient, and 100

the notches in the edges of the shank, as hereinbefore explained, will cut their own bearings, thereby preventing the shank from turning.

5 Having thus described my invention, what I claim as new, and desire to secure by Letters Patent, is—

1. In a drawer-pull, a flat shank adapted at one end to be secured in position within a drawer, the other end being riveted or otherwise secured to a yoke, as described, substantially as and for the purpose specified.

2. In a drawer-pull, the tube B, arranged inferiorly of the knob A, in combination with the ferrule E, yoke B, and shank C, substantially as and for the purpose set forth.

In testimony whereof I affix my signature in presence of two witnesses.

FRIEND W. SMITH.
